CLAIM

The ornamental design for a spherical toy water ball, as shown and described.

DESCRIPTION

FIG. 1 is a perspective view of a spherical toy water ball in a closed state in accordance with my new design;

FIG. 2 is another perspective view thereof, showing the spherical toy water ball in an open state, and,

FIG. 3 is similar to FIG. 2, but viewed from another aspect. The broken lines depict portions of the spherical toy water ball that form no part of the claimed design.
